UNITED STATES PATENT OFFICE

JOHN B. GOODWIN, OF SAN FRANCISCO, CALIFORNIA

INTERNAL-COMBUSTION ENGINE

Application filed November 9, 1925. Serial No. 67,738.

This invention relates to internal combustion engines, of the type generally known as Diesel or oil engines, and has for its object the provision of an improved lighter engine 5 of this character, by eliminating the sudden and enormous strains that may arise in the ordinary Diesel engine on combustion. More particularly, the invention has reference to the provision of means for reducing the pressure within the main or working cylinder at 10 which combustion is effected without a material reduction in the power or working efficiency of the engine. These means comprise an auxiliary or compensating cylinder 15 in communication with the working cylinder, the compensating cylinder piston being normally opposed by resilient force, such as a spring or compressed air. This force may be varied to correspond to the maximum 20 pressure selected for the working cylinder, thus when said maximum pressure in the working cylinder is reached, the compensating piston is acted upon to overcome its opposing force, and as it moves into its cylinder 25 it increases the volume of the working cylinder in a proper ratio, thus preventing the further increase of pressure in the working cylinder and at the same time maintaining the maximum predetermined pressure 30 while the piston of the compensating cylinder completes its stroke, or until combustion is effected. The compensating piston may be described as having a cushioning effect. After combustion is effected, the compensating 35 piston is restored to its normal position by the opposing force acting thereon. This will be better understood from the detailed description hereinafter.

Another object of the invention is to provide 40 an improved device for controlling the volume of the fuel injection into the working cylinder.

A further object of the invention is to provide 45 novel means for controlling the time of said fuel injection.

A still further object of the invention is to provide means for securing atomization of 50 widely varying quantities of fuel, that is, from a few grains per injection to the maxi-

mum that may be burnt in the working cylinder.

A further object of the invention is to provide 55 an improved solid injection nozzle, in which small openings are eliminated to prevent clogging from dirt or impurities usually present in the fuel oil. While air injection nozzles may accomplish the same result, the chilling effect of the blast requires the use of higher pressures, and such nozzles are more 60 complicated and expensive, requiring high pressure air compressors.

The invention possesses other advantageous features, some of which with the foregoing will be set forth at length in the following description where I shall outline in full that form of the invention which I have selected for illustration in the drawings accompanying and forming part of the present specification. In said drawings I have shown 70 several forms of my invention, but I do not desire to be limited thereto, since the invention as set forth in the claim may be embodied in a plurality of other forms.

Referring to the drawings: 75 Figure 1 is an elevation of an engine embodying my invention illustrating the working and compensating chambers and parts of the controlling mechanism, said latter parts being shown holding the fuel discharge piston in its retracted position.

Fig. 2 is a vertical section taken on the line 2-2 of Fig. 1, but with the fuel discharge piston and its cooperating parts shown in its extended position.

Fig. 3 is a section taken on the line 3-3 of Fig. 1.

Fig. 4 illustrates the pressure chamber for the compensating piston and an air receiver connected therewith.

Fig. 5 is a sectional view of a modified form of means for opposing the compensating piston.

Fig. 6 shows an indicator card of the usual Diesel engine with the changes in characteristics obtained by an engine embodying my invention also indicated thereon.

In the drawings I have shown a main or working cylinder 1, provided with the usual exhaust 2, air inlet 3 as indicated in dotted 100

lines and piston 4, as best shown in Fig. 2. The upper end 5 of the cylinder 1 is preferably formed with a spherical surface. At its upper end the cylinder 1 is provided with a compensating cylinder 6 in communication with said cylinder 1, the compensating cylinder 6 being provided with a piston 7. In small engines in which but a single fuel nozzle is employed, the compensating cylinder 1 is preferably positioned on one side of the vertical axis of the cylinder 1; however in large engines which have cylinders of a larger bore, the compensating cylinder is preferably coaxial with the working cylinder and a plurality of nozzles are arranged concentric therewith. The face 8 of piston 7 is also spherical and coincides with the spherical surface 5 when the piston 7 is in its normal position as shown in Fig. 2. It is to be understood that the working cylinder head may assume other forms. Preferably the cylinders 1 and 6 are formed by a single casing 9, which is provided with the usual water cooling passage 10 having an inlet 11 and outlet 12. The cylinder 6 is open at both ends and the casing 9 is formed with an external flange or shoulder 13 adjacent the free end of cylinder 6 to support a pressure chamber 14, which may be secured thereto in any suitable manner such as by bolts 14', shown in Fig. 1. The chamber 14 is of greater diameter than the cylinder 6 and the rear portion of piston 7 is extended into the chamber 14 to form a piston 15 therein as shown in Fig. 2. The piston 7 is preferably in the form of a hollow body forming a cooling chamber 16 in which water is circulated through the pipes 17. A receiver 18 is provided which communicates with chamber 14 through a pipe 19. The receiver 18 is provided for the purpose of providing a large volume of air under compression to oppose the movement of piston 15 so that the displacement of air due to the movement of said piston shall not cause an undue rise in the pressure of the air resisting the movement of said piston 15 and thereby raise the maximum pressure within the working cylinder. From the foregoing detailed description, the operation of the parts described will be readily understood from a brief description in connection with Fig. 5.

In the first downward stroke of the working piston 4, air enters the working cylinder 1 through inlet 3 in the usual manner. At the end of the stroke, the working cylinder 1 is full of air at practically atmospheric pressure, ready for the compression stroke. At this time, the piston 7 is in its lower or outer position by reason of the pressure within the cylinder 14, as shown in Fig. 2. In the next stroke of the piston 4, the air is compressed to the required pressure, usually about 400 pounds per square inch, while the temperature rises to between 1000° F. to 1100° F.

Let it be assumed that the maximum pressure

selected for working is 400 pounds per square inch and that the working cylinder 1 and piston 4 are designed to produce a maximum compression of say 500 pounds per square inch on a full compression stroke. Obviously, if means are connected with the cylinder 1 adapted to yield when the selected maximum pressure is reached, 400 pounds per square inch in the present case, the pressure in the cylinder 1 will not exceed that pressure, although the piston 4 has not completed its compression stroke. In the present form of device embodying my invention, the piston 7 provides such yielding means. The chamber 14 and its piston 15, are designed so as to apply an opposing force to the inward movement of the piston 7 up to the maximum pressure selected for the cylinder 1. Thus, when the pressure within the working cylinder 1 reaches, say 400 pounds per square inch, the pressure within cylinder 14 is overcome and the compensating piston 7 moves into its cylinder 6. This action obviously increases the volume of the cylinder 1 and the several parts are so designed that the increase in volume is just sufficient to maintain the compression within the cylinder 1 at the predetermined maximum value.

Obviously, as the pressure within the working cylinder 1 decreases, that is after the combustion takes place and the piston 4 starts on its downward stroke, the piston 7 moves toward its open end and follows up the piston 4 to the limit of its travel, thereby maintaining the above mentioned maximum working pressure in cylinder 1 for a considerable portion of the travel of the piston 4. To compensate for leakage losses in the chambers 14 and 18, and more particularly, to provide a dash pot for the compensating piston 7 and prevent injury thereto by its forcible return when the shoulders forming the piston 15 strike against the shoulders of the cylinder 6, I have provided an inlet 20, having a suitable check valve 21, extending into the chamber 14 on the return side of the piston 15, and an outlet 22, similarly positioned which communicates through a by-pass 23 with the compression side of the piston 15. The by-pass is controlled by a suitable check valve 24. Thus, when the piston 15 makes its compression stroke, air enters the cylinder 14 on its lower side through inlet 20, and when the piston 15 moves in the opposite direction, this air is pumped through the outlet 22 and by-pass 23 into the cylinder 14 on the compression side of the piston 15, and the pressure in the cylinder 14 thus maintained. The passage of the air from the rear of the piston 15 however is sufficiently retarded by the valve 24 to provide a dash pot action and prevent the forcible return of the same against the casing 9. To prevent the building up of excessive pressures within said cylinders 14 and 18 a relief valve

25, of the automatic or manual type, may be provided. It is of course understood that in a multi-cylinder type of engine, the several cylinders 14 may be connected to a common chamber 18, designed to maintain the necessary pressure. As shown in Fig. 5, the receiver 18 may be omitted and the chamber 14 may be provided with a suitable spring 25' to perform functions similar to that shown above.

10 It is of course understood that air is supplied to chambers 14 and 18 by any suitable compressing means, not illustrated, and that the pressure in said chambers may be varied. 15 By varying the resistance opposing the movement of the compensating piston, compensation may be made for differences in altitude and for ignition points of fuels. This feature renders the engine particularly suitable 20 for aero service as well as automotive work in mountainous countries, and also makes it readily adaptable for various fuels. Another particular advantage of this arrangement is that the smaller engines may readily be started 25 ed for example by a hand crank, by reducing the pressure opposing the compensating piston, thereby reducing the compression and employing for starting purposes only a lighter grade of fuel than that on which the 30 engine usually runs.

The advantageous results obtained by this arrangement will be better understood from the indicator card shown in Fig. 6, in which the full lines have reference to an engine not 35 provided with my compensating cylinder. Therein, *ab* represents the first or suction stroke, *bc* the compression of the air more or less adiabatically, *cd* the combustion during the admission portion of the next stroke, and 40 *de* the following expansion of the mixture until the exhaust valve opens at *e*, when for the remainder of the stroke *ef*, the pressure falls more rapidly as some of the gases are expelled; *fa* represents the final stroke in 45 which all the products of combustion are exhausted through the exhaust valve. Let it be assumed that at the point *x* on *bc* the compression has reached the maximum selected pressure of 400 pounds per square inch. At 50 this instant, the piston 7 functions as above described, and the pressure remains at this value as indicated by *xy* in dotted lines which indicates the combustion and partial expansion during the initial portion of the next stroke. The dotted line *yz* indicates the following expansion of the mixture until the 55 exhaust valve opens in an engine embodying my invention. From this it will be seen that with a lower pressure in the working cylinder, I secure substantially the same power as has heretofore been secured with greater pressures.

The means for supplying fuel oil to the working cylinder 1 comprise a fuel supply pipe 26 which communicates through pas-

sages 27, 28 and 29 with said cylinder 1. The passage 27 communicates with one end, shown as the upper end in Fig. 2, of a small chamber or reservoir 30 for holding a charge of fuel oil and is controlled by an inlet valve 31 acting against the inner end of the passage 27. Within the chamber 30, is a washer 32, urged toward the bottom of said chamber and away from the valve 31 by suitable means such as a coiled spring 33. A coiled spring 34 acting against the washer 32 urges the valve 31 in its seat. The valve 31 is provided with a stem 35, extending through the springs 33 and 34 for positioning the same. The passage 29 is controlled by an inlet or injection valve 36 which is seated against the end of the same within the working cylinder 1, and more fully described hereinafter. From this it will be seen that when fuel is supplied through the supply pipe 26, the valve 31 is unseated, opening communication with the fuel charge chamber 30, and this chamber, as well as passages 28 and 29 are filled with fuel oil until the same is expelled therefrom by means now to be described.

The opposite or lower end of the fuel charge chamber or cylinder 30, communicates through a sleeve 37 with a cylinder 38, and a rod 37' is slidable therein and projects therefrom. A piston 39 is within the cylinder 38 and means are provided for reciprocating the piston 39 intermittently at predetermined periods, as will be later described. Obviously, the upward movement of the piston 39 toward the sleeve 37 causes it to engage the rod 37' and push it into the chamber 30 thereby forcing the fuel oil therefrom into the working cylinder 1 through the passages described.

It is clear that the stroke of the piston 39 determines the quantity of fuel oil supplied to the working cylinder and means are provided for varying the stroke thereof. It is also apparent that the piston 39 must operate at definite predetermined periods so as to force the fuel oil into the working cylinder 1 at the time the desired pressure is built up therein. To accomplish these results, I have provided novel, simple and efficient means shown in Figs. 1, 2 and 3.

Within the cylinder 38, I have provided a strong heavy coil spring 40, which acts against the rear face of the piston 39 and against the bottom of the cylinder. In the present case, I have shown the bottom of the cylinder 38 as formed by a cover plate 41, bolted to the casing of cylinder 38. The lower end of spring 40 is also shown as seated in a cup 42, which may be moved by means of screws 43 whereby the tension of the spring 40 may be adjusted in a manner readily understood. It is obvious that other means may be used for actuating the piston 39, such for example as an air chamber similar to the chamber 14 above described. The cylinder

38 is also provided with a by-pass 44 connecting the opposite sides of the piston 39, to provide a dash pot similar to that described above in connection with piston 15. The piston 39 is provided with a stem 45, shown as hollow in the present case, although not necessarily so, which projects through the cylinder bottom 41. The lower end of the stem 45 is provided with a solid bifurcated member 46 which pivotally supports a link 47 between its bifurcations on a pin 48. The opposite end of the link 47 is connected with a rod 49, which is reciprocated, vertically as shown in Figs. 1 and 2, by a suitable cam, at definite intervals. The cam is not shown as this arrangement is well understood in the art and not deemed necessary to be shown herein. Between the pin 48 and the rod 49, I have provided an adjustable fulcrum about which 10 the link 47 acts. By varying this fulcrum the stroke of the piston 39 may be regulated, and in this manner, the supply of fuel supplied to the working cylinder 1 regulated. This fulcrum comprises a roller 50 mounted on a 20 crank shaft 51 which is journaled in a substantially vertical member 52, extending alongside of the projecting portion of the piston stem 45. The upper end of the member 52 is pivotally connected with the bottom plate 41 of cylinder 38 and at its opposite end is pivotally connected with a manually operated lever 53, which is shown as horizontal. From the foregoing description, it will be seen that the roller 50 is eccentrically 30 mounted on the member 52, and that the movement of the member 52 by the rod 49 varies the distance of the fulcrum of the link 47, thereby controlling the distance of the back stroke of the piston 39 and consequently the amount of fuel discharged to the working cylinder.

The upward movement of the rod 49 causes the piston 39 to move downwardly, or outwardly in its cylinder, compressing the spring 40, and placing the piston in operative position to discharge the fuel oil into the working cylinder 1; however, since this action must take place in the briefest interval and at a definite predetermined time, means are provided for holding the piston 39 in such operative position, and releasing the same at the proper instant, thus permitting the spring 40 to act and operate the piston. For this purpose, a tripping member 54 is pivoted on the member 52 at 55, one end 54' of which is adapted to strike a locking member 56 which is fixed on the crank or cam shaft 51 of the roller 50. The movement of the member 56 in a counter-clockwise direction is prevented 50 by a stop 57, and it is urged against said stop by a spring 57'. The opposite end 54" of the tripper 54 is engaged by a trigger 58, pivoted on a collar 59 which loosely surrounds the projecting end of valve stem 45. The collar 59 60 has a relatively fixed position in which it is

held by a spring 60 acting upon it and a suitable collar 61 fixed on the said stem 45. The spring 60 urges the collar 59 against another fixed element hereinafter referred to. The trigger 58 is in the form of a lever pivoted at an intermediate point on a fulcrum 62. As above stated, one of its ends is adapted to strike the tripper 54, and its opposite end is normally urged downwardly by a spring 63. Between the fulcrum 62 and the said opposite end, the trigger 58 is engaged by a link 64 which is reciprocated by a rod 65. The rod 65 is reciprocated by means of a cam, not shown, but which acts at predetermined intervals in a well understood manner. Having 70 described the structural details of the time controlling means for the fuel discharge, it is believed that a short description of the operation will suffice.

Let it be assumed that the rod 49 has moved 75 upwardly in which case the stem 45 has moved downwardly, compressing spring 40, the action having taken place through the link 47 which is fulcrumed on the roller 50. At this time, the member 56 abuts the stop 57, having been moved to this position by spring 57'. At this time, the axis of the roller 50 is below the axis of the crank shaft 51 and the piston is thereby held in its retracted position. At the proper instant, the rod 65 is moved upwardly causing the trigger arm 58 to move downwardly, pushing the shoulder 54" about the pivot 55, and moving the tripping member end 54' counter-clockwise, thereby moving the member 56 clockwise. The motion of member 56 displaces the axis of the crank shaft 51 to one side of the axis of the roller 50, and since the spring 40 is acting to push the piston 39 up, the link 47 is acting upwardly upon the roller 100 50. Since the axis of the crank shaft 51 is now off center with respect to the axis of roller 50, the result is that the arm 56 is thrown back quickly, thereby relieving the fulcrum point of support and allowing the piston 39 105 to move upwardly. Through the action of a spring 66, the tripper 54 is restored to its normal position, and the members 50 and 56 are restored to their former positions by the action of spring 57'. The cycle of operation described is repeated for the next fuel discharge.

In order to provide means for adjusting the time of discharge, the upper face of the collar 59 is provided with a series of inclined surfaces 67, adapted to cooperate with similar 110 inclined surfaces 68 on a collar 69, which abuts against the bottom plate 41 of cylinder 38. The collar 69 is rotatable on the stem 45 and provided with an operating handle 70. Thus by rotating the collar 69, the collar 59 115 may be adjusted vertically on the stem 45, and consequently the time at which the trigger 58, which is carried on the collar 59, operates the tripper 54 may be varied.

The valve 36 which controls the fuel sup- 120

ply inlet is provided with a stem 87 which extends into a sleeve 88 which is provided with suitable external threads 89 to engage a threaded aperture 90 in the casing 9. Preferably, the sleeve 88 is closed at its lower end 71, through which the stem 87 extends, and said sleeve is provided with apertures 72 in its wall to bring its interior in communication with the passage 28. The inner end of the 5 valve stem is provided with a washer 73 held in place by a nut 74, said washer acting a shoulder for one end of a coiled spring 75, the opposite end of said spring acting against the inner surface of the end 71. The aperture 90 is enlarged near its upper end to accommodate an external shoulder 76 on the sleeve 88, and is held in the opening 90 by a nut 77. The external surface of the sleeve 88 from the shoulder 76 to its upper end is 10 smooth. By rotating the sleeve 88 the unit is moved from and toward the valve seat 36. Obviously, this movement varies the distance between the end 71 and washer 73, thereby varying the tension of the spring 75. By 15 varying the tension of this spring, the distance the valve seat 36 opens may be controlled and in this manner, I control the rate of flow of the fuel oil to the working cylinder. Varying the tension on the inlet valve spring not 20 only has an effect on the distance the valve opens, but it also governs the degree of atomization and in its relationship to the tension of spring 40 the duration of the injection period. This variation of atomization 25 is due to the variation of fuel injection pressures. The upper end of the sleeve 88 is closed by a threaded cap 78, which is provided with a central passage 79, closed by a thumb screw 80, which provides a bleed valve 30 to permit the exhausting of any air from the fuel supply system that may be in the same before starting the engine.

It will be observed that the passage 29 is 35 comparatively large and that the valve is seated on the inner end thereof. By this arrangement, clogging by dirt and other impurities in the fuel oil is prevented, since the passage is large enough to permit the passage therethrough of the same ordinarily, and 40 if such particles lodge in the passage, they are expelled therefrom when the fuel is injected into the cylinder 1. As shown in Fig. 2, the valve 36 is moved outwardly and 45 may be adjusted to secure a fine atomization, the comparatively sharp edges of the valve seat producing the atomizing action.

From the foregoing, it will be seen that I 50 have produced a highly flexible engine in which a fine atomization of widely varying 55 quantities or qualities of fuel is possible, the flexibility being further facilitated by a refined control of the time of fuel injection as well as the quantity of fuel injected. Flexibility over a wide range of speeds is not a 60 characteristic of the usual type of heavy oil

engines; however an engine embodying my invention is of light weight and highly flexible, especially adapting it to a wide range of service such as for example automotive, rail, aero and marine service. While I have shown 70 my invention as embodied in a two cycle type of engine, it is of course understood that the invention may be embodied in other types.

I claim:

An internal combustion engine comprising- 75 a working cylinder, a compensating cylinder, a wall enclosing a pressure chamber of greater diameter than the compensating cylinder, a piston within the compensating cylinder adapted to be acted upon by pressure within the working cylinder, a piston provided in said pressure chamber and secured to said first piston, and means for maintaining the pressure within said pressure chamber, said means including 80 a by-pass formed in and providing communication thru said wall from one side of the piston provided in the pressure chamber to the opposite side thereof, a check valve secured in said wall and adapted to work in said by-pass, and an air inlet valve opening into the atmosphere from one side of the piston provided in the pressure chamber. 85 90

In testimony whereof, I have hereunto set my hand.

JOHN B. GOODWIN.
